INTERLINER PACKAGE

Thomas G. Sadler, Attleboro, Mass., assignor to
 Sadler Bros., Inc., a corporation of Massa-
 chusetts

Application January 29, 1941, Serial No. 376,426

6 Claims. (Cl. 206—52)

This invention relates to a package for the interliner used by opticians in the shimming of frames for eye glasses; and the invention has for one of its objects to place this interliner material in a more convenient form for handling and maintaining the same in a cleaner condition.

Another object of the invention is to provide a package from which the material may be easily and quickly drawn and clipped off at the desired length, leaving the remainder of the package in its original packaged form.

Another object of the invention is to maintain a portion of the interliner projecting from the package in order that it may be readily grasped for pulling the desired amount from the package.

Another object of the invention is a simplified method of assembling the package.

With these and other objects in view, the invention consists of certain novel features of construction, as will be more fully described, and particularly pointed out in the appended claims.

In the accompanying drawings:

Fig. 1 is a plan view of the package;

Fig. 2 is an edge view of the package;

Fig. 3 is a central sectional view through the package;

Fig. 4 is an edge view of the package, showing some of the interliner material as drawn therefrom;

Fig. 5 is a central sectional view through the package, with the interliner material removed and showing one disc of the casing;

Fig. 6 is a sectional view illustrating the positioning of the pin in the package;

Fig. 7 is a sectional view showing the pin as positioned;

Fig. 8 is a view similar to Fig. 7 illustrating in dotted lines the pin as being gripped for winding the interliner in the package;

Fig. 9 is a plan view of a modified form of package showing the notch with the interliner protruding therefrom; and

Fig. 10 is an edge view of the modified form of package shown in Fig. 9.

Interliner material of Celluloid or like material in strip form, usually arcuate in cross section, and used for shimming eye glass frames, is usually furnished in loose rolls or in metal boxes. The material in such form is difficult to handle and store. Some care must be taken that the coils do not become disrupted to such an extent as to become snarled or tangled with other working equipment, and the handling of coils of even short lengths is clumsy and difficult. In order to make more accessible this material and also

to provide for more convenient handling of the same, I have provided a package in which the material is provided in a spiral coil, held in a casing of a pair of transparent discs whose edges are so formed as to come together and provide a complete package enclosing the coil, or optionally notched to maintain the material protruding therefrom, and yet the discs are sufficiently resilient so that the material may be obtained by spreading the discs sufficiently to grasp the edges of the material and then pull the material by the spreading of the discs progressively around their periphery; and the following is a more detailed description of the present embodiment of this invention, illustrating the preferred means by which these advantageous results may be accomplished.

With reference to the drawings, the sheet stock parts of my package consist of a core 10, Celluloid discs 12 each beveled or flaring inwardly as at 18 and a pair of Celluloid washers 16. Each of these parts is provided with an opening and is assembled upon an arbor 25 (see Fig. 6) of a size to just fit this opening and bring the openings and the various parts into registry. This pin is urged upwardly by a spring 26 located in bore 27 in a block 28 carrying a cap 29 thereon and is shouldered as at 30 to limit the upward extension of the pin.

A pin 14 is used to hold the package in assembled relation and is square in cross section and sharpened at its end as at 32. This pin is forced downwardly by a plunger 31, as shown in Fig. 6. The plunger forces the arbor 25 inwardly by reason of the resilience of the spring 26 and causes the pin 14 to force its way through the washers, discs and core to become rigidly fixed in all of these parts by reason of its square cross section, as illustrated in Fig. 7.

Two projecting portions of the pin, as shown in Fig. 8, may be grasped in a chuck 34 and turned so as to assemble the interliner material 21 which is started by inserting one end in slot 23 in the core, as illustrated in Fig. 5, and then by turning, the interliner material is spirally wound as at 11 into the package and is of a width to be guided by its opposite edges contacting the discs 12.

After winding the interliner into position, the ends of the pin 14 are cut off and caps 17 are positioned over the ends of the pin, as illustrated in Figs. 2, 3, 4, or 10.

In some instances, the interliner may be completely enclosed within the disc 12, as illustrated in Figs. 1, 2, and 3, while in other cases, the disc

may be notched as at 36 so as to maintain an end of the interliner in exposed position for ready grasping by the hand.

From the manner of assembly, it will be readily apparent that the pin locks all of the parts together against relative rotation. It is desirable that there be a rotation of the large discs 12 relative to the remaining parts for ease in unreeing as these are the parts usually grasped in one hand, and accordingly as these parts are thin, I may cause them to be rotatable relative to the rest of the assembly by merely twisting them upon the pin to enlarge the hole and make the same round instead of square, that rotation of these discs may be had.

The washers may be of a color distinguishing from the color of the core, while the caps may be of still a different color or of a color matching the color of the core so as to provide a handsome contrast and a decorative package.

The discs 12 are transparent so that the interliner material may be viewed through the discs. The thin, transparent discs 12, however, are sufficiently flexible so as to easily move into dotted line position as shown at 20 in Fig. 3 or as shown in Fig. 4. When the end 21 of the material is grasped and pulled, the discs will revolve, as will also the material, about the core, and the discs will be progressively spread apart about their periphery as shown in Fig. 4, permitting the desired amount of material to be drawn from position.

It will be apparent that this device may be made in various sizes to receive different coil lengths of interliner material.

I claim:

1. A package of interliner material comprising a core, a spiral coil of a length of material about said core, a casing comprising discs extending over either side of said coil to confine and align the coil between them, and a pin extending centrally through said core, said core being fixed on said pin and said discs being rotatable with reference thereto, and means extending radially from said pin and engaging the outer surface of said discs to secure the same in said relation.

2. A package of interliner material comprising a core, a spiral coil of a length of material about said core, a casing comprising discs extending over either side of said coil to confine and align the coil between them, a pin extending centrally through said core and discs to hold the parts in assembled relation, said core being fixed on said

pin and said discs being rotatable with reference thereto, and washers on the outer surface of said discs and fixed to said pin.

3. A package of interliner material comprising a core, a spiral coil of a length of material about said core, a casing comprising discs extending over either side of said coil to confine and align the coil between them, a pin extending centrally through said core and discs to hold the parts in assembled relation, said core being fixed on said pin and said discs being rotatable with reference thereto, washers on the outer surface of said discs and fixed to said pin, and covers secured to said washers over the ends of said pin.

4. A package of interliner material comprising a spiral coil of a length of material, a casing comprising discs extending over either side of said coil to confine and align the coil between them, washers engaging the outer surface of said discs and a pin extending through said discs and fixed to said washers to secure the discs in said relation, both of said discs at a location radially outwardly beyond said coil and peripherally thereof extending toward each other to engage and provide a closure for said package, and a notch in said inwardly extending portion of the discs to permit the coiled material to protrude therethrough.

5. A package of interliner material comprising a spiral coil of a length of material, a casing comprising discs extending over either side of said coil to confine and align the coil between them, washers engaging the outer surface of said discs and a pin extending through said discs and fixed to said washers, to secure the discs in said relation, both of said discs at a location radially outwardly beyond said coil and peripherally thereof extending toward each other to engage and provide a closure for said package.

6. A package of interliner material comprising a spiral coil of a length of material, and having an axial dimension of the width of the material, a casing comprising discs extending over either side of said coil with their inner surfaces a distance apart substantially the width of the coil material, to confine and align the coil between them, and means to secure the discs in said relation, both of said discs at a location radially outwardly beyond said coil and peripherally thereof extending toward each other to engage and provide a closure for said package.

THOMAS G. SADLER.
